CHOCOLATE RABBIT

Albert F. Storz, Primos, and Robert G. Seidman, Philadelphia, Pa., assignors to Mel Richman Design Associates Inc., Bala-Cynwyd, Pa., a corporation of Pennsylvania

Application October 15, 1959, Serial No. 57,944

Term of patent 14 years

(Cl. D82—2)

Fig. 1.

Fig. 2.

Fig. 3.

Fig. 4.

We claim:

The ornamental design for a chocolate rabbit, substantially as shown.
